C. M. JACOBS

SHOE FOR DISK HARROWS

Filed May 26, 1922

Inventor
C. M. Jacobs

R. J. McNamee

Attorney

UNITED STATES PATENT OFFICE.

CLARENCE M. JACOBS, OF BUTLER, KENTUCKY.

SHOE FOR DISK HARROWS.

Application filed May 26, 1922. Serial No. 563,860.

To all whom it may concern:

Be it known that CLARENCE M. JACOBS, a citizen of the United States, residing at Butler, in the county of Pendleton and State of Kentucky, has invented certain new and useful Improvements in Shoes for Disk Harrows, of which the following is a specification.

My invention relates to a shoe adapted to be mounted upon the tongue of a disk harrow, for use in the place of the ordinary wheeled truck, while not necessarily restricted to this use.

An important object of the invention is to provide a device of the above mentioned character, which is simple in construction, strong, durable, is vertically adjustable, and has means whereby the double-tree may be connected with the front clevis at different elevations, which will effect the rolling action of the shoe, to a considerable extent.

Other objects and advantages of the invention will be apparent during the course of the following description.

In the accompanying drawings forming a part of this specification, and in which like numerals are employed to designate like parts throughout the same.

Fig. 1 is a side elevation of a device embodying my invention, and,

Fig. 2 is a perspective view of the same.

In the drawings, wherein for the purpose of illustration is shown a preferred embodiment of my invention, the numeral 5 designates the tongue of a disk harrow. This tongue is connected with the usual frame 6, carrying the disks 7, as shown.

My device embodies a rear clevis 8, which is formed from a single piece of metal, bent to provide a vertical sleeve 9, which is cylindrical, and a U-shaped socket 10, connected therewith by intermediate necks 11. The U-shaped socket receives the forward end of the tongue 10, and is rigidly secured thereto, by bolts 12 or the like.

The numeral 13 designates a vertical shaft, slidably mounted within the sleeve 9, and having a shoe 14 rigidly secured to its lower end. This shoe is relatively wide and longitudinally curved, the curvature gradually increasing toward the forward end thereof. The shoe 14 also tapers toward its forward upper end.

The numeral 15 designates a front clevis,

embodimenting an elongated vertical plate 16, 55 having a pair of spaced strap ears 17 formed integral therewith. These strap ears surround the shaft 13 above and below the sleeve 9, and are adapted to be contracted to have clamping engagement with the shaft 60 13, by means of bolts 18.

The plate 16 has vertically spaced openings 19, formed therein, to receive the clevis of the double tree, whereby such double tree may be connected with the front clevis at 65 different elevations. This is important, as by lowering the connection the pull by the draft animals will tend to throw the rear portion of the shoe 14 into action. The rolling or sliding action of the shoe is therefore 70 regulated, to some extent. It is obvious that the shaft 13, and shoe 14 are free to turn laterally in steering, and the shaft 13 is also vertically adjustable within the strap ears 17. 75

In the use of the device, the harrow is drawn forwardly over the ground, in the usual manner. The shoe slides upon the ground, and thus takes place of the usual wheeled truck. 80

Attention is called to the fact that the bolts 18 may be so adjusted that the vertical shaft 13 will be frictionally held within the strap ears against turning movement under ordinary working conditions, but should the shoe 14 encounter an unusual obstacle such as a large stone, the shaft 13 could then turn within the strap ears 17, to permit of the lateral movement of the shoe 14. The shock would be absorbed by the frictional engagement between the elements 13 and 17, to permit of the lateral movement. The shoe 14 would subsequently return to the neutral position, upon the continued operation of the machine, or may be returned thereto by the operator. It will also be seen that the higher the draft line is placed on the plate or clevis 16, the less vertical component and the greater tendency of sinking of the blade 14 into the soil and therefore a greater need for the sharp curvature of the shoe 14, and the increasing in width of the same rearwardly. 90 95 100 105

It is to be understood that the form of my invention herewith shown and described is to be taken as a preferred example of the same, and that various changes in the size, shape, and arrangement of parts may be

resorted to without departing from the spirit of my invention or the scope of the subjoined claims.

Having thus described my invention, I claim:

1. The rear clevis having a socket to be secured to the tongue of a disk harrow or the like, said rear clevis embodying a substantially vertical sleeve, a substantially vertical shaft pivotally mounted within the sleeve, a ground engaging shoe carried by the lower end of the shaft and being longitudinally curved and increasing in curvature forwardly, a front clevis embodying a substantially vertical plate having a pair of strap ears receiving the shaft above and below the rear clevis, said substantially vertical plate having vertically spaced means for connection with a draft appliance which may be attached to the plate at different elevations, and means for effecting a clamping engagement between the strap ears and the substantially vertical shaft whereby the shaft is held against turning movement under ordinary working conditions and may turn when the shoe is subjected to an abnormal force tending to shift it laterally.
2. The rear clevis to be secured to the tongue of a disk harrow or the like and having a substantially vertical sleeve, a substantially vertical shaft, held within the sleeve, a longitudinally curved ground shoe carried by the lower end of the shaft, a front clevis embodying an ear receiving the shaft, and means to clamp said ear to the shaft in the manner whereby the shaft is held against turning movement within the ear under normal working conditions and may turn therein when the shoe is subjected to an abnormal force tending to shift it laterally.

3. A clevis device to be secured to the tongue of a disk harrow or like implement embodying a substantially vertical ear, a substantially vertical shaft mounted within the ear, a ground engaging shoe secured to the lower end of the shaft and extending longitudinally beyond said substantially vertical shaft, and means for clamping said ear to the shaft so that said shaft is held against turning movement under normal working conditions and may turn when an abnormal force is applied to said shoe tending to shift the shoe laterally.

4. A clevis device adapted for connection to the tongue of a disk harrow or like implement, embodying substantially vertical plate having vertical spaced means whereby a draft appliance may be attached to the plate at different elevations, a substantially vertical shaft secured to the clevis device, and a ground engaging shoe secured to the lower end of the shaft and being longitudinally curved and increasing in curvature forwardly and upwardly.

5. A clevis device adapted for connection to the tongue of a disk harrow or like implement, embodying substantially vertical plate having vertical spaced means whereby a draft appliance may be attached to the plate at different elevations, a substantially vertical shaft secured to the clevis device, and a ground engaging shoe secured to the lower end of the shaft and being longitudinally curved and increasing in curvature forwardly and upwardly, said shoe also tapering forwardly.

In testimony whereof I affix my signature.

CLARENCE M. ^{his} X JACOBS.
